CLAIM

The ornamental design for a toy railroad freight car, as shown and described.

DESCRIPTION

FIG. 1 is a perspective view of a toy railroad freight car showing my new design;

FIG. 2 is a top plan view thereof;

FIG. 3 is a bottom plan view thereof;

FIG. 4 is a side elevational view thereof, the side opposite being a mirror image;

FIG. 5 is a front elevational view thereof; and

FIG. 6 is a rear elevational view thereof.

FIG. 1

FIG. 5

FIG. 2

FIG. 6

FIG. 4

FIG. 3
